DESIGN FOR A COMBINED RIVET AND COLLAR

George S. Wing, Hermosa Beach, Calif.

Application August 20, 1943, Serial No. 110,968

Term of patent 14 years

(Cl. D54—9)

To all whom it may concern:

Be it known that I, George S. Wing, a citizen of the United States, residing in Hermosa Beach, in the county of Los Angeles and State of California, have invented a new, original, and ornamental Design for a Combined Rivet and Collar, of which the following is a specification, reference being had to the accompanying drawing, forming part thereof.

Fig. 1 is a side elevation of a combined rivet and collar, showing my design.

Fig. 2 is an end view, looking in the direction of arrows 2—2 of Fig. 1.

Fig. 3 is an end view, looking in the direction of arrows 3—3 of Fig. 1.

Fig. 4 is an exploded view of the combined rivet and collar.

The dominant portion of the design is that shown in solid color and in full lines in the drawing.

I claim:

The ornamental design for a combined rivet and collar, substantially as shown and described.

GEORGE S. WING.
